CLAIM

The ornamental design for a handle for home appliance, as shown and described.

DESCRIPTION

FIG. 1 is a perspective view of a handle for home appliance, showing our new design;

FIG. 2 is a front elevation view thereof;

FIG. 3 is a rear elevation view thereof;

FIG. 4 is a side elevation view thereof;

FIG. 5 is a another side elevation view thereof;

FIG. 6 is a top plan view thereof;

FIG. 7 is a bottom plan view thereof; and,

FIG. 8 is another perspective view thereof in an environment of use.

The broken lines shown represent unclaimed subject matter and form no part of the claimed design.
